UNITED STATES PATENT OFFICE.

LANSING ONDERDONK, OF NEW YORK, N. Y., ASSIGNOR TO UNION SPECIAL MACHINE COMPANY, OF CHICAGO, ILLINOIS, A CORPORATION OF ILLINOIS.

SEWING-MACHINE.

1,325,037.

Specification of Letters Patent. Patented Dec. 16, 1919.

Application filed August 21, 1915. Serial No. 46,607.

To all whom it may concern:

Be it known that I, LANSING ONDERDONK, a citizen of the United States, residing at New York, in the county of New York, 5 State of New York, have invented certain new and useful Improvements in Sewing-Machines, of which the following is a description, reference being had to the accompanying drawing and to the figures of reference marked thereon.

10 The invention relates to new and useful improvements in sewing machines, and more particularly to the feeding mechanism for manipulating the material.

15 An object of the invention is to provide a feeding mechanism wherein an upper feed dog coöperates with the presser foot in feeding the material, and wherein the mechanism for operating the feed dog and presser foot are so timed and constructed 20 that the feed dog and presser foot are in engagement with the material for a time interval between the lifting movements of the feed dog and presser foot.

25 A further object of the invention is to provide a device of the above character wherein the lifting mechanism for the feed dog includes devices having a lost motion so that a certain portion of the movements 30 of the lifting devices become ineffective to lift the feed dog.

These and other objects will in part be obvious and will in part be hereinafter more fully described.

35 In the drawings, which show by way of illustration one embodiment of the invention:—

Figure 1 is an end view of a sewing machine having my improvements applied 40 thereto;

Fig. 2 is a rear view of the same, certain parts being broken away;

Fig. 3 is a transverse sectional view along 45 one side of the feed dog, showing the upper feed dog, the lower feed dog, and a portion of the work support, the presser foot and the needles;

Fig. 4 is a plan view of the parts shown in Fig. 3;

50 Fig. 5 is a view showing more or less diagrammatically the essential parts of the upper feed dog operating mechanism and the

presser foot with the presser foot in raised position;

Fig. 6 is a similar view with the presser 55 foot lowered and the feed dog raised;

Fig. 7 is a detail view, partly in section, showing the upper eccentric and rock frame for raising and lowering the feed dog;

Fig. 8 is a detail, partly in section, showing the operating mechanism for moving the feed dog back and forth;

Fig. 9 is a detail showing the operating arm for lifting the presser bar;

Fig. 10 is a detail view showing the rock 65 lever for lifting the presser foot and feed dog;

Fig. 11 is a detail showing the lower feeding mechanism.

The invention consists broadly in providing a sewing machine having a work support with a presser foot which engages the material on the work support and an upper feed dog which coöperates with the presser foot in feeding the material. The feed dog 75 and presser foot are connected to a rock lever which is actuated so as to alternately raise the presser foot and feed dog so that the presser foot may be positively raised during the feeding movements of the feed 80 dog, and the feed dog may be positively raised for its return or idle movement. The mechanism between this rock lever and the feed dog includes devices which have a lost movement or an ineffective movement so 85 that the feed dog and presser foot will remain on the material for a time interval before either is given its lifting movement. The purpose of this is to prevent the rebound of either the feed dog or the presser 90 foot from causing irregularities in the feed.

Referring more in detail to the drawings, my improved sewing machine consists of a supporting bed 1 having a standard 2 carrying an overhanging arm 3 in which a needle bar 4 reciprocates. This needle bar as herein shown is provided with two pairs of needles 5 and 6. Any suitable complementary stitch forming mechanism may be used to coöperate with said needles beneath the 100 work support.

Mounted on the supporting bed is a work support 7. Located beneath the work support is a feeding mechanism consisting of a

lower feed dog 8 which is mounted on a feed bar 9, and this feed bar is in turn pivoted to a feed rocker 10. The feed rocker 10 is pivoted to the supporting bed 1 and is oscillated back and forth by suitable connections to the main shaft 11. The feed bar 9 is raised and lowered by an eccentric 12 on the main shaft. This part of the feeding mechanism is of the well-known construction and further detail description thereof is not thought necessary.

The material is held on the work support by a presser foot 13. This presser foot is carried by a presser bar 14 mounted in the overhanging arm 3 of the machine. The presser bar may be raised by a hand lever 15 or by a lever 16 connected to a suitable treadle or knee shift. The presser bar is held down to hold the presser foot on the work support by a spring 17 which bears on a pin 18 projecting laterally from the presser bar 14.

The feeding mechanism in addition to the above parts also includes an upper feed dog 19. This feed dog is adjustably connected to a feed bar 20 which is pivoted at 21 to a depending arm 22 fixed to a shaft 23. The shaft 23 is mounted in bearings 24—24 carried by the overhanging arm 3. This shaft 23 carries a second depending arm 25 which is fixed to the shaft by suitable clamping screws. The shaft 23 at its lower end carries a ball stud 26 which is engaged by an eccentric 28 on the main shaft 11. As this main shaft rotates, the arm 25 will be oscillated and this, in turn, will oscillate the shaft 23 which moves the feed bar 20 back and forth, thus giving the feeding movement to the feed dog 19.

The feed dog 19 is raised and lowered by a rock lever 29. This rock lever 29 is fulcrumed on an arm 30 which is rigidly fixed to the presser bar 14. The arm 31 of the rock lever 29 extends substantially in a horizontal direction from the fulcrum point of the rock lever, and a rod 32 is pivoted to the outer end of this arm. This rod depends from the arm in substantially a vertical position and extends through a perforated lug 33 which is fixed to the feed bar 20 by a clamping screw 34. The upper face of the feed bar 20 is recessed to receive this lug so that a single clamping screw will hold the same in fixed position relative to the feed bar. On the lower end of the rod 32 there is an adjustable nut 35, the end of the rod being threaded to receive this nut. A lock nut 36 serves to hold the adjustable nut 35 in adjusted position. Also threaded onto the rod 32 is a nut 37. A coiled spring 38 encircles the rod 32 and bears against the nut 37 at one end and against the lug 33 at its other end.

The other arm 39 of the rock lever 29 projects upwardly in substantially a vertical direction. At the upper end of this arm

there is a ball stud 40. A link 41 is connected to said ball stud 40. Mounted on the shaft 23 is a rock frame 42. This rock frame has a downwardly and forwardly projecting arm 43 (see Fig. 2). Said last-named arm 70 is provided with a ball stud 44, and the link 41 is connected at its other end to this ball stud 44. The rock frame is formed with a laterally projecting arm 45 which is slotted, as at 46. A rod 47 co-operates with an eccentric 48 on the main shaft 11 and is connected to a stud 49 which is adjustable in the slot 46. As the main shaft 11 rotates, the eccentric 48 will oscillate this rock frame 42 and through the link 41 will oscillate the 80 rock lever 29.

The arm 30, which serves as a fulcrum support for the rock lever, projects rearwardly from the presser bar 14 and is forked to engage a guide bar 50. This prevents the presser bar from turning and holds the arm 30 so that it moves up and down without lateral oscillation.

The feed dog 19 is serrated or toothed on its lower face in the usual manner. Said feed dog at its rear end extends upwardly, as at 51, and engages a seat formed in a vertically depending portion 52 of the feed bar 20. A clamping screw 53 holds the feed dog on the feed bar and permits the same 95 to be adjusted vertically. The presser foot 13 is formed with two needle openings 54 and 55 which receive respectively the pairs of needles 5 and 6. The presser foot is carried by a shank 56. This shank is forked, 100 and the arms 57 and 58 of the fork carry the foot portion 13. Said presser foot 13 is provided with a longitudinal slot 59 which extends from its rear end to a point adjacent the extreme end of the upturned toe of 105 the foot. The feed dog 19 moves back and forth in this slot 59. The toe of the presser foot extends above the feed dog 19 so that there is ample room for the feed dog to move back and forth and engage the material as it is fed underneath the up-turned portion of the presser foot.

A bracket arm 60 is clamped to the lower end of the guide bar 50, and at its lower end carries a roller which projects laterally underneath the feed bar 20. This roller serves as a rest for the feed bar 20 when there is no material in the machine.

The movements of the rock lever 29 in one direction raise the presser foot and 120 lower the upper feed dog into engagement with the material, while the movements of this rock lever in the other direction raise the feed dog and lower the presser foot onto the material. When the rock lever 29 125 is moved to the left, as viewed in Figs. 5 and 6, the rod 32 will first be lowered, permitting the feed dog to engage the material. The coiled spring 38 is of less tension than the spring 17 which holds the presser foot 130

on the material. Therefore, after the feed dog has engaged the material, further movement of the rock lever in the same direction will cause the coils of the spring 38 to come 5 into contact and said spring to become, in effect, a rigid member. The rod 32 moves downward through the perforated lug 33 carrying the nut 35 away from this lug to the position shown in Fig. 5. After this 10 coiled spring 38 has collapsed and become a rigid member, then further movement of this rock lever 29 in the same direction will raise the presser bar and, consequently, the presser foot from the material.

15 It will thus be seen that the feed dog engages the material an interval of time before the presser foot is raised, this interval of time being that portion of the movement of the rock lever which is necessary to bring the 20 coils of the spring 38 into contact and convert said spring into a substantially rigid member. A movement of the rock lever 29 in the opposite direction will lower the presser foot into engagement with the material, 25 after which the bar 32 will be raised, bringing the stop nut 35 into engagement with the lug 33. A continued movement of this rock lever to the right, as viewed in Figs. 5 and 6, will then raise the feed dog from the material, and while said feed dog is raised, the 30 arm 22 is oscillated to return the feed dog to its forward position for the next feeding movement. It is understood, of course, that this arm 22 is oscillated in the other direction, while the feed dog is in engagement with the material and while the presser foot is raised for feeding the material. From 35 the above, it will be apparent that the presser foot will engage the material an interval of time before the feed dog is raised, and this interval of time depends upon the movement of the rock lever necessary to bring the stop nut 35 on the rod 32 into engagement with the lug 33.

40 45 It will be apparent from the above description that I have provided an actuating mechanism for lifting the feed dog and presser foot which operates first to lower one of these members onto the material where it remains for an interval of time before the other is raised; then the last-named member will be again lowered onto the material and remain there an interval of time before the other one is raised. In other words, there is 50 an interval of time between each lifting movement wherein both the feed dog and presser foot remain on the material, and this is brought about through the lost motion in the connection between the rock lever 55 and the feed dog.

60 It is well-known that in sewing machines of the type above described, which are particularly adapted for operating upon heavy material, such as leather, there is more or 65 less rebound when the presser foot or the

feed dog strikes the material, which is due in part to the rapid movement of the parts and in part to the heavy pressure necessary to properly hold and properly feed these heavy materials. If one element is raised 70 just as the other engages the material, this rebound may become effective to release the material from any hold thereon by the feed dog or the presser foot which results in irregularity of feed, but in my improved 75 mechanism, where there is an interval of time between the lifting of the parts engaging the upper face of the material, whatever rebound there may be either in the presser foot or the feed dog will have no 80 effect upon the feeding of the material, as this rebound in the element striking the material is over before the other element is lifted from the material.

85 It will be understood, of course, that, when the presser bar is raised, the rock lever 29 will be held from oscillation by the link 41 and, therefore, lifting of the presser bar will also bodily raise the rock lever and lift the feed bar 20 and the feed dog 19.

90 It is obvious that minor changes in the details of construction and the arrangement of parts may be made without departing from the spirit of the invention, as set forth

95 appended claims.

Having thus described the invention, what is claimed as new is:—

1. A feeding mechanism for sewing machines including in combination a work support, a lower feed dog and means for operating the same, a presser foot, an upper feed dog engaging the material on the work support, means for moving said upper feed dog back and forth, and devices for alternately raising and lowering said upper feed dog and presser foot, said devices including 100 a rock lever and connecting means for causing the feed dog and presser foot to simultaneously remain in engagement with the material for an interval of time before 110 either the feed dog or presser foot is lifted.

105 2. A feeding mechanism for sewing machines including in combination, a work support, a presser foot, an upper feed dog engaging the material on the work support, means for moving said upper feed dog back and forth, and means for alternately raising and lowering the feed dog and presser foot, said means including devices having a lost motion whereby the presser foot and feed dog 115 will remain on the material for an interval of time prior to the lifting movements thereof.

120 3. A feeding mechanism for sewing machines including in combination, a work support, a presser foot, an upper feed dog engaging the material on the work support, means for moving said upper feed dog back and forth, and means for alternately raising and lowering said feed dog and presser 125 130

foot including a rock lever, means for oscillating the rock lever, means for positively connecting the rock lever to the presser foot, and devices for connecting said rock lever to the feed dog, said devices having a lost motion whereby the feed dog and the presser will remain on the material for an interval of time prior to the lifting movements thereof.

10 4. A feeding mechanism for sewing machines including in combination, a work support, a presser foot, an upper feed dog engaging the material on the work support, means for moving said upper feed dog back and forth, and means for alternately raising and lowering the feed dog and presser foot, said means including a rock lever, means for oscillating the rock lever, means for positively lifting the presser foot from

15 20 said rock lever, a rod connected to the rock lever and to the feed dog, said rod having a lost motion connection with one of said parts, a spring interposed between the rock lever and the feed dog, said spring being constructed so as to collapse and become a rigid member whereby the feed dog and presser foot may remain for an interval of time upon the material before their lifting movement.

25

30 5. A feeding mechanism for sewing machines including in combination, a work support, a presser foot, an upper feed dog engaging the material on the work support, means for moving said upper feed dog back and forth, and means for alternately raising and lowering said feed dog and presser foot, said means including an arm rigidly connected to the presser bar, a rock lever fulcrumed on said arm, one arm of said 35 rock lever being positioned substantially horizontally and parallel with the feed bar carrying the feed dog, a rod connected to said arm, a perforated lug carried by the feed bar through which said rod extends, an 40 adjustable stop on the lower end of said rod, a coiled spring encircling said rod, and an abutment carried by the rod for said spring, said spring engaging the abutment on the rod and said perforated lug and 45 being so constructed as to collapse and become a rigid member whereby the same may serve as an abutment for the lifting of the 50 presser bar.

6. A feeding mechanism for sewing machines including in combination, a work support, a presser foot, an upper feed dog engaging the material on the work support, means for moving said upper feed dog back and forth, means for alternately raising and lowering the feed dog and presser foot, said means including an arm rigidly attached to the presser bar, a rock lever pivoted to said arm, one arm of said rock lever extending upwardly in a substantially vertical direction, a rock frame, an arm de-

pending from said rock frame in a substantially vertical position, a link disposed substantially horizontally, and connecting the arm on the rock frame to the arm of said rock lever, the second arm of said rock lever being disposed substantially horizontally, a rod pivoted thereto and extending downwardly through a perforated lug carried by the feed bar for the feed dog, an adjustable stop carried by the lower end of said rod, an abutment carried by the rod, a coiled spring encircling said rod and bearing against said abutment and said lug. 70 75

7. A feeding mechanism for sewing machines including in combination, a work support, a presser foot, an upper feed dog engaging the material on the work support, means for moving said upper feed dog back and forth, means for alternately raising and lowering the feed dog and presser foot, said means including an arm rigidly attached to the presser bar, a rock lever pivoted to said arm, one arm of said rock lever extending upwardly in a substantially vertical direction, a rock frame, an arm depending from said rock frame in a substantially vertical position, a link disposed substantially horizontally and connecting the arm on the rock frame to the arm of said rock lever, the second arm of said rock lever being disposed substantially horizontally, a rod pivoted thereto and extending downwardly through a perforated lug carried by the feed bar for the feed dog, an adjustable stop carried by the lower end of said rod, an abutment carried by the rod, a coiled spring encircling said rod and bearing against said abutment and said lug, and means whereby the abutment and said rod may be adjusted for varying the tension of the coiled spring.

8. A feeding mechanism for sewing machines including in combination, a work support, a presser foot, an upper feed dog engaging the material on the work support, means for moving said upper feed dog back and forth, means for alternately raising and lowering the feed dog and presser foot, said means including an arm rigidly attached to the presser bar, a rock lever pivoted to said arm, one arm of said rock lever extending upwardly in a substantially vertical direction, a rock frame, an arm depending from said rock frame in a substantially vertical position, a link disposed substantially horizontally and connecting the arm on the rock frame to the arm of said rock lever, the second arm of said rock lever being disposed substantially horizontally, a rod pivoted thereto and extending downwardly through a perforated lug carried by the feed bar for the feed dog, an adjustable stop carried by the lower end of said rod, an abutment carried by the rod, a coiled spring encircling said rod and bear- 110 115 120 125 130

ing against said abutment and said lug, a spring for depressing the presser foot, said spring being of greater tension than said coiled spring, and said coiled spring being 5 so proportioned as to become of greater tension than the spring for the presser bar during the oscillating movements of the rock lever whereby said coiled spring may

serve as an abutment for the lifting of the presser foot.

In testimony whereof I affix my signature in the presence of two witnesses.
